(57) **CLAIM**

The ornamental design for a gear cutting tool, as shown and described.

DESCRIPTION

This application incorporates by reference Design Patent Application No. 2015-009462, filed in Japan on Apr. 27, 2015. All the material from the Design Patent Application No. 2015-009462, filed in Japan on Apr. 27, 2015 which is essential to the claimed design is included in this application. It is understood that any material in the Design Patent Application No. 2015-009462, filed in Japan on Apr. 27, 2015 which is not present in this application forms no part of the claimed design.

FIG. 1 is a perspective view of a gear cutting tool.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof.

FIG. 8 is an enlarged cross-sectional view taken along the line 8-8 in FIG. 2.

FIG. 9 is an enlarged view of the portion 9-9' in FIG. 1; and,

FIG. 10 is an enlarged view of the portion 10-10' in FIG. 2.
